[57] CLAIM

The ornamental design for an industrial container, as shown and described.

DESCRIPTION

FIG. 1 is a rear perspective view of a first embodiment of a container showing my new design;

FIG. 2 is a front elevational view thereof;

FIG. 3 is a right side elevational view thereof, the left side being a mirror image of the right side shown;

FIG. 4 is a rear elevational view thereof;

FIG. 5 is a top plan view thereof;

FIG. 6 is a bottom plan view thereof;

FIG. 7 is a rear perspective view of a second embodiment of a container showing my new design;

FIG. 8 is a front elevational view thereof;

FIG. 9 is a right side elevational view thereof, the left side being a mirror image of the right side shown;

FIG. 10 is a rear elevational view thereof;

FIG. 11 is a top plan view thereof; and,

FIG. 12 is a bottom plan view thereof.

The broken line showing of an axle and wheels is for illustrative purposes only and forms no part of the claimed design.
